UNITED STATES PATENT OFFICE.

CHARLES H. HEYWOOD AND DENISON E. TRAVIS, OF WAUKEGAN, ILLINOIS, ASSIGNEES
TO UNITED STATES ENVELOPE COMPANY, OF SPRINGFIELD, MASSACHUSETTS, A
CORPORATION OF MAINE.

FEEDING MECHANISM FOR PAPER OR CARDBOARD.

1,218,861.

Specification of Letters Patent. Patented Mar. 13, 1917.

Application filed March 26, 1908. Serial No. 423,312.

To all whom it may concern:

Be it known that we, CHARLES H. HEYWOOD and DENISON E. TRAVIS, citizens of the United States, residing at Waukegan, in the county of Lake and State of Illinois, have invented certain new and useful Improvements in Feeding Mechanism for Paper or Cardboard, of which the following is a specification, reference being had to the accompanying drawings, forming a part thereof.

The object of our present invention is to provide a mechanism for feeding sheets of paper, cardboard, or the like, to machines adapted to perform certain operations thereon, such, for example, as folding, cutting, slitting, or printing. For the purpose of illustrating the construction and operation of a feeding mechanism embodying our invention, we have shown and described the same in connection with a printing press for printing envelop blanks, which are supported upon a feeding table in a pile or stack and individually fed to the cylinders of a rotary printing press. By means of the mechanism embodying our invention the topmost blank in the pile or stack is selected and fed forward to the cylinders of the press, and during its transit is gaged and brought into proper position or registration to receive the impression, and these results are accomplished by certain novel features of construction and arrangement of parts as hereinafter described and pointed out in the annexed claims.

Figure 1 is a side elevation of a printing press and mechanism for feeding envelop blanks thereto embodying our present invention, with a portion shown in vertical longitudinal section on a plane indicated by the broken line 1—1, Fig. 2.

Fig. 2 is a plan view of the same, certain parts being broken away and shown in horizontal section.

Fig. 3 is a partial end view as seen from the right with reference to Fig. 1, the type cylinder, a portion of the frame and other parts of the machine being removed and certain parts shown in vertical cross section.

Fig. 4 is a vertical longitudinal section on the line 4—4, Fig. 2.

Fig. 5 is an enlarged sectional and diagrammatic view of the nipper and associated parts, illustrating the operation of the nipper.

55.

Fig. 6 is a plan view of the mechanism for picking up the blanks from a stack or pile and feeding them to the reciprocating carriage, and

Figs. 7 and 8 are diagrammatic views showing respectively side and plan views of a modification of the feeding mechanism adapted to a stack of rectangular sheets.

Similar reference letters and figures refer to similar parts in the different views.

65.

Although for the purpose of illustration our invention is shown and particularly described as embodied in a printing press, it is also applicable to other machines to which blanks or sheets of paper or cardboard or similar material are to be fed.

Referring to the accompanying drawings 1 denotes the framework of the machine, in which is journaled a driving shaft 2, an impression cylinder 3, a type cylinder 4, 75 and a shaft 5 carrying a feed roll 6. The impression cylinder 3 is rotated by a gear 7 mounted on the driving shaft 2 and engaging a gear 8, the gear 8 imparting rotary motion to the type cylinder 4 through a gear 9, as shown in Fig. 2. The feed roll 6 is driven by a belt connection from a pulley 10 on the driving shaft 2, and runs in contact with an idle feed roller 11, located below it in an opening in the bed 12.

85.

Mounted upon the framework of the machine at one end are vertical brackets 13, 13, for supporting that portion of the feeding mechanism which is employed to select the blank from a pile or stack and present it to the feed rollers 6 and 11. The blanks to be fed are supported in a pile or stack 14 upon a table 15, to which an upward feeding motion is imparted by a mechanism such as is in common use in envelop or other machines, but which is not herein shown or described, as it forms no part of our present invention.

90.

That part of the feeding mechanism supported by the brackets 13, 13, is shown in plan view in Fig. 6 and in vertical sectional view in Fig. 1, and it consists of a rocking shaft 16 to which is attached a frame 17, comprising arms 18 and 19 provided with bearings for a tube 20, capable of a sliding motion in the arms 18 and 19 and connected

105.

at its upper end by a flexible connection, not shown, with an air pump by which air is periodically exhausted from the tube 20. The lower end 21 of the tube 20 is adapted 5 to be brought into contact with the uppermost blank in the stack 14, and, when the air is exhausted from the tube 20, it forms a suction pickup, so that when the tube is raised the uppermost blank is lifted from the stack 10 in the manner common to suction pickups as they are now employed in envelop and printing machines.

Journaled in the brackets 13 is a rocking shaft 22 to which is clamped an arm 23, provided at its free end with a slot 24 which incloses a roll 25, carried by a block 26 which is clamped to the suction tube 20. In addition to the rocking shafts 16 and 22 the brackets 13 support a third rocking shaft 20 27, to which is clamped arms 28, 28, in the free ends of which is journaled a shaft 29 carrying rolls 30, 30, arranged to contact at proper intervals with idle rolls 31, carried upon stands attached to the framework of 25 the machine upon opposite sides of the back-flaps 32 of the envelop blanks, supported upon the feed table 15.

Rotary motion is imparted to the shaft 29 from the shaft 5 through the gears 33, 30 34 and 35, Fig. 6. The rocking shaft 16 carries a radial arm 36 which is operatively connected by a link 37 with a radial arm 38, carried upon one end of a rocking shaft 39. The opposite end of the rocking shaft 35 39 carries a radial arm 40, the free end of which is provided with a cam roll 41 actuated by a suitably shaped cam 42, carried upon the shaft of the impression cylinder 3. The rocking shaft 22 is provided with a 40 radial arm 43, operatively connected by a link 44 and cam roll 45 with a cam 46 carried on the shaft of the impression cylinder 3, Fig. 2. The rocking shaft 27 carries a radial arm 47 connected by a link 48 with a rocking arm 49, carrying a cam roll 50 which is actuated by a cam 51 on the shaft of the impression cylinder 3. Cams 42, 46 and 51 are single acting, and the motion of the rocking shafts 16, 22 and 27 are reversed 50 by means of suitable springs applied thereto, in the present instance, by torsional springs 52, 53 and 54.

By the rocking of the shaft 16 the suction tube 20 is given an angular movement forward and back between the positions shown in Fig. 1 and indicated by the broken lines 55, Fig. 1, and a vertically sliding movement is given to the suction tube 20 by means of the rocking shaft 22, which serves to carry 60 the suction tube 20 downward into contact with the uppermost blank as the suction tube is swung to the left in Fig. 1, and then an upward movement before the suction tube is swung to the right. As the end of the 65 suction tube is brought into contact with the

envelop blank air is exhausted therefrom, and a vacuum maintained until the tube has reached the extent of its forward angular movement, as indicated by the broken lines 55, when the vacuum is broken to release the 70 envelop blank.

The suction exerted by the tube 20 during its compound movement causes the back-flap of the topmost envelop blank to be first raised from the stack and then carried forward from the position of the blanks, shown by a solid line in Fig. 6, to the position indicated by the broken line 56, Fig. 6. When the upward and forward movement of the envelop blank has been effected, the shaft 27 is rocked to depress the rotating rolls 30, 30, against the end flaps of the envelop blank, which has been lifted by the upward longitudinal movement and then drawn by the angular movement of the suction tube 20 between the rolls 30 and the idle rolls 31. The rotation of the rolls 30 project the envelop blank forward between the feed rolls 6 and 11, which continue the movement of the blank over the bed 12 of the machine. 90

The bed 12 has a central opening and is spanned with parallel longitudinal strips 57, which support the envelop blank in its forward movement. Beneath the central opening of the bed 12 is a reciprocating carriage 58, which is supported and guided by a horizontal rod 59, arranged lengthwise of the machine and transversely to the axes of the cylinders 3 and 4. The reciprocating carriage 58 is held from turning upon the rod 59 by a lateral arm 60, provided with a roller 61 which is confined between horizontal guide ways 62. Journaled in upwardly projecting ears on the carriage 58 is a transverse rock shaft 63 provided with arms 64, 105 to which are adjustably attached gage stops 65. The transverse rock shaft 63 carries an arm 66, which is provided with a roller 67 running on a cam shaped guide way 68, having an upward incline 69 at the end nearest 110 the impression cylinder 3.

A spring 70 holds the roller 67 against the guide way 68 and the adjustable gage stops 65 normally project above the longitudinal blank supporting strips 57. Journaled in 115 downwardly projecting ears on the reciprocating carriage 58 is a transverse rock shaft 71, upon which are mounted a pair of arms 72 called jogggers. The rock shaft 71 carries an arm 73 which is provided with a 120 roller 74, held by a spring 75 against a cam shaped guide way 76, having a downward incline 77 at the end farthest from the impression cylinder 3.

A reciprocating movement is imparted to 125 the carriage 58 by a cam 78 attached to the shaft of the type cylinder 4, and engaging with a roller 79 on one arm of a bell crank lever 80. The other arm of the bell crank lever 80 is provided with an adjustable 130

5 roller 81, engaging one arm of a two armed lever 82 on a transverse rock shaft 83. The transverse rock shaft 83 is provided with an upwardly extended arm 84 connected at its upper end by a link 85 with the carriage 58. The cam 78 is single acting, and the motion of the carriage 58 is reversed by the action of a spring 86 connected with one arm of the lever 82.

10 When the carriage 58 is at the end of its movement nearest the feed roller 6, the roller 74 passes downward over the incline 77, bringing the arm 73 and joggers 72 into the positions indicated by the broken lines 87 and 88, Fig. 1, and carrying the joggers below the supporting surface of the longitudinal strips 57, to permit the envelop blank, as it is projected forward by the feed rollers 6 and 11, to pass over the joggers into position 20 behind the gage stops 65, which are then in the position indicated by the broken lines 89, Fig. 1.

As the carriage moves forward the roller 74 passes up the incline 77, thereby rocking the shaft 71 and swinging the joggers forward against the edge of the envelop blank to push it forward into contact with the gage stops 65, said stops and joggers having been adjusted so that the normal space between them is substantially equal to the width of the envelop blank at its points of contact with the gage stops and joggers. The continued movement of the carriage 58 slides the envelop blank along the longitudinal supporting strips 57, to hold it in proper registration between the joggers 72 and the gage stops 65. As the carriage 58 reaches the end of its movement nearest the impression cylinder 3, the roller 67 rides 40 upon the inclined surface 69 of the guide way 68, thereby rocking the shaft 63 and depressing the gage stops 65 below the supporting surface of the strips 57, bringing the gage stops into the position indicated by the broken lines 90, Fig. 1, in order to permit the continued feeding motion of the envelop blank over the gage stops.

50 The continued feeding motion of the envelop blank is accomplished by a gripping mechanism carried by the impression cylinder 3, and comprising a gripping face 91 formed at or adjacent to one of the longitudinal edges of the tympan face of the cylinder, and a pivoted nipper 92 coacting with the gripping face 91 to seize the advancing edge of the envelop blank. A rocking shaft 93 is journaled in the cylinder 3 parallel with its axis and projecting therefrom through one of the cylinder heads. The rocking shaft 93 is provided near its inner end with a radial arm 94, and at its outer end it carries a two armed right angled lever 95, having one of its arms parallel with the radial arm 94 carried by the inner end of the rocking shaft 93.

In the radial arm 94 and the parallel arm of the lever 95 is journaled a shaft 96 parallel with the rocking shaft 93. The shaft 96 is provided at its outer end with an arm 97, and at its inner end and on opposite sides of the radial arm 94 with segment gears 98. One end of the nipper 92 is forked to inclose the sides of the radial arm 94. The forked end of the nipper is pivoted to the radial arm 94, and upon each side thereof is provided with gear teeth 99 concentric with its pivot and engaging segment gears 98, as shown in Figs. 4 and 5. One arm of the two armed lever 95 is provided with a roller 100, which is yieldingly held by a spring 101, connecting said lever with the adjacent cylinder head, against the peripheral face of a stationary cam 102, fixed upon a sleeve which forms the journal box of the cylinder 3, as shown in Fig. 2. Similarly, the arm 97 is provided with a roller 103, which is yieldingly held by a spring 104 against a stationary cam 105, held by the sleeve of the journal box of the cylinder 3.

The driving connections of the carriage 58 are adjusted to advance the envelop blank at a speed corresponding with the peripheral speed of the impression cylinder 3. The gage stops 65 and joggers 72 move forward with the envelop blank when it is gripped by the nipper 92, and during the depression of the gage stops into the position shown by the broken lines 90, Fig. 1, the joggers are moved forward into the position indicated by the broken lines 106, Fig. 1. The movements of the carriage 58 and the impression cylinder 3 are so timed, that the forward edge of an envelop blank advancing with the carriage passes under the gripping face 91 of the impression cylinder 3 and over the nipper 92, as shown in Fig. 5.

The roller 100 in passing from the smaller to the larger part of the cam 102 swings the arm 94 backward, and carries the nipper underneath the advancing envelop blank opposite the gripping face 91. The roller 103 in passing from the smaller to the larger part of the cam 105 swings the nipper inward and grips the envelop blank against the face 91 and, as the gage stops 65 have at this point been depressed into the position indicated by the broken lines 90, Fig. 1, the blank is released from the carriage as the latter approaches the limit of its advanced movement. When the carriage is reversed the gage stops 65 assume the position indicated by the broken lines 89; and the joggers 72 assume the position indicated by the broken lines 87 and 88, allowing the next succeeding blank to be received from the feed rollers 6 and 11.

The complete feeding motion of the envelop blank comprises four distinct stages: first, the selection and presentation of the blank to the feed rollers 6 and 11; second,

the projection of the blank forward over the reciprocating carriage by the feed rollers 6 and 11; third, the advance movement of the blank by the reciprocating carriage 58; and 5 fourth, the seizure and final movement of the blank by means of the rotating gripping mechanism. The mechanism employed in these four stages of feeding movement are complete and independent in their functions, 10 although they are correlated by their connection with the single driving shaft 2 and successively act upon the envelop blank.

The mechanism employed for the first stage raises the envelop blank from the stack 15 and moves it forward to the feed rollers; the mechanism of the second stage projects the envelop blank over the reciprocating carriage; the mechanism of the third stage continues the forward movement of the envelop 20 blank and, during its period of movement, brings it into registration with the gage stops 55 and in position for subsequent operation upon the envelop blank.

Various changes in the details of construction and in the arrangement of parts may be 25 made to adapt the mechanism to different machines for various purposes, without departing from the principle and intended scope of our invention.

30 In Figs. 7 and 8 I have shown a slight modification in the arrangement of the mechanism for the first stage of the feeding movement, by which it is adapted for feeding square sheets. In the modified form 35 shown in diagrammatic view in Figs. 7 and 8 the idle rolls 31, which are arranged on opposite sides of the stack 14, are exchanged for a continuous roll 107 which is placed in front of the stack 108 of square sheets.

40 Swinging feed rolls 109 are carried upon separate shafts 110, 111, driven with uniform form rotation from opposite sides of the machine, thereby forming a gap between the rolls 109 for the swinging movement of the 45 suction tube 20.

The suction tube 20, as used in machines of this class, is termed a pickup or a suction pickup, as its principal function is to engage by suction the uppermost blank in the stack 50 and to lift it from the stack in position to be moved forward by the feeding mechanism. This suction pickup is provided at its lower end with a mouth adapted to form an air tight joint when it is pressed in close 55 contact with the blank. Air is exhausted from the pick-up intermittently by the action of an air pump having a flexible connection with the pick-up, and when the vacuum is broken the blank becomes released from 60 the end of the pick-up. We have not shown in detail the construction of the pick-up or its connected air pump, as these features are in common use and their construction and operation will be understood by those 65 conversant with this class of machines.

The vacuum is broken in the pickup after it has reached the limit of its forward angular movement, and after the rolls 30, 30, have been depressed to coöperate with the idle rolls 31, in order to continue the forward movement of the envelop blank between the feed rolls 6 and 11. During the continued forward movement of the envelop blank, it is guided between the feed rolls 6 and 11 by the inclined surfaces 112, formed 70 on the ends of the longitudinal supporting strips 57.

We claim,

1. In a feeding mechanism of the kind specified, means for supporting the blank 80 to be fed, a suction pickup adapted to engage the forward edge of said blank, a constantly operating blank forwarding means, and a pair of normally separated rolls interposed in the path of said blank between said 85 constantly operating forwarding means and the edge of said blank, means for operating said pickup to engage the blank and to deposit it between the separated rolls of said pair, and means for thereafter bringing said 90 rolls together to feed the blank to said constantly operating forwarding means.

2. In a mechanism of the kind specified, means for supporting the blank to be fed, 95 a suction pickup adapted to engage the forward edge of said blank, pairs of normally separated rolls on each side of said pickup and in advance of the forward edge of said blank, means for operating said pickup to carry the edge of the blank, by the exertion 100 of a tensile strain on the blank between the separated rolls of said pairs, and means for thereafter bringing the rolls of said pairs together to continue the forward movement 105 of said blank.

3. In a feeding mechanism of the kind specified, means for supporting a blank to be fed, a suction pickup adapted to engage the blank at its extreme forward point, pairs of feed rolls disposed rearwardly of the 110 point of engagement of said pickup and in advance of the longitudinally aligned portions of the forward edge of said blank, and means for moving said pickup forwardly, whereby the forward edge of said blank 115 is drawn into the bight of said feed rolls by the exertion of a tensile strain on the blank.

4. In a feeding mechanism of the kind specified, supporting means for the blank 120 to be fed, pairs of feed rolls disposed in advance of the correspondingly longitudinally aligned portions of the forward edge of said blank, a suction pickup adapted to engage said blank at a portion thereof in 125 advance of the bight of said feed rolls, and means for moving said pickup forwardly to carry the edge of said blank into the bight of said rolls by the exertion of a tensile strain on said blank.

5. In a feeding mechanism of the kind specified, a support for the material to be fed, a rocking shaft above said support, a swinging frame carried by said shaft, a suction pickup slidable in said frame, a second rocking shaft, an arm carried by said second shaft with its free end engaging said pickup to impart an up and down movement thereto in said frame, a common cam shaft for controlling the rocking movement of both of said rocking shafts, two pairs of normally separated feed rolls having their axes located in a vertical plane behind the mouth of said suction pickup and upon opposite sides 10 of the plane of its movement, and means for bringing said rolls together at the end of the swinging movement of said pickup.
6. In an envelop machine, a blank feeding mechanism comprising the following instrumentalities:— a positively engaging constantly operating forwarding means, a suction pickup adapted to engage the forward edge of the blank, and a pair of normally separated rolls in the path of said blank 15 between its edge and said constantly operating forwarding means, means for operating said pickup to carry the blank into a

position to be operated upon by said rolls when they are brought together, means for releasing said blank from said pickup, and 30 means for thereafter bringing said rolls together to project the blank into the constantly operating forwarding means.

7. In a feeding mechanism of the kind specified; a support for the material to be 35 fed, a movable suction pickup adapted to engage the material near one of its edges, pairs of feed rolls located on opposite sides of the line of movement of said pickup, means for intermittently separating said 40 rolls to render them inoperative as feeding means, means for moving said pickup forwardly between the upper rolls of said pairs to draw the material by the exertion of a tensile strain thereon between said rolls 45 when the same are separated, and means for bringing said rolls together at the end of the movement of said pickup.

Dated this seventeenth day of March, 1908.
